(57) **CLAIM**

The ornamental design for a refillable pill card for wallet, as shown and described.

DESCRIPTION

FIG. 1 is a perspective view of the refillable pill card for wallet with the doors in a closed position, showing my new design;

FIG. 2 is a front view thereof;

FIG. 3 is a side view thereof;

FIG. 4 is a top plan view thereof;

FIG. 5 is a bottom plan view thereof;

FIG. 6 is a front view with the doors in an open position;

FIG. 7 is a side view thereof;

FIG. 8 is a top plan view thereof; and,

FIG. 9 is a bottom plan view thereof.

The area within the broken line boundaries of FIGS. 6 and 7 form no part of the claimed design.
